UNITED STATES PATENT OFFICE.

JOHN J. DAVIS AND THOMAS DUNCAN, OF MUNCIE, INDIANA.

DESIGN FOR A CHURN-DASH.

SPECIFICATION forming part of Design No. 26,882, dated April 13, 1897.

Application filed January 19, 1897. Serial No. 619,811. Term of patent 3½ years.

To all whom it may concern:

Be it known that we, JOHN J. DAVIS and THOMAS DUNCAN, citizens of the United States, residing at Muncie, in the county of Delaware and State of Indiana, have invented a certain new and original Design for Churn-Dashes, of which the following is a specification, reference being had to the accompanying drawings, which fully illustrate our design.

The leading feature of our design consists in a cylindrical body having its outer surface provided with longitudinal corrugations, the upper end of the body terminating in a conical-shaped top, the body being provided with a central opening of two diameters, the opening in the lower portion of the body being of greater diameter than the opening at the upper end.

In the drawings, 1 designates the body, cylindrical in cross-section and having longitudinal corrugations 2 upon its outer surface. The upper end of the body is conical, as at 3. Extending longitudinally of the body and centrally thereof is an opening of two diameters, the larger opening 4 in the lower part of the body being of greater diameter than the opening 5 within the upper end of the body. The apex of the conical top 3 terminates coincidentally with the wall of the opening 5.

What we claim is—

The design for a churn-dash substantially as shown and described.

In testimony whereof we affix our signatures in presence of two witnesses.

JOHN J. DAVIS.
THOMAS DUNCAN.
